The ornamental design for an ejaculation promotion apparatus, as shown and described.

(51) **LOC (9) Cl.** **28-03**

DESCRIPTION

(52) **U.S. Cl.** **D24/215**

FIG. 1 is a perspective view of the ejaculation promotion apparatus according to the invention;

(58) **Field of Classification Search** D24/200,

FIG. 2 is a front elevation view of the ejaculation promotion apparatus of FIG. 1;

D24/211-215, 141; 601/27, 28, 33, 40, 46,
601/47, 48, 63, 80, 99, 104, 112, 113, 114,
601/119, 122, 125, 129, 134, 135, 137, DIG. 12,
601/DIG. 13, DIG. 14, DIG. 15, DIG. 16,
601/DIG. 17

FIG. 3 is a rear elevation view of the ejaculation promotion apparatus of FIG. 1;

See application file for complete search history.

FIG. 4 is a left side elevation view of the ejaculation promotion apparatus of FIG. 1;

(56) **References Cited**

FIG. 5 is a right side elevation view of the ejaculation promotion apparatus of FIG. 1;

U.S. PATENT DOCUMENTS

FIG. 6 is a top plan view of the ejaculation promotion apparatus of FIG. 1; and,
